NOZZLE

Fred W. Funke, Oakland, Calif., assignor to Robert St. J. Orr, San Francisco, Calif.

Application March 23, 1946, Serial No. 656,663

2 Claims. (Cl. 210—166)

1

This invention relates to nozzles and has for one of its objects the provision of a nozzle that includes several passageways therein and a valve for controlling the flow of liquid through said passageways as desired, including a blow-off type of strainer in one of said passageways and which latter passageway communicates with a spray port or tip.

Another invention is the provision of a nozzle provided with a valve that is easy to turn regardless of the water pressure against the same, and easy to service and recondition.

A still further object of the invention is a nozzle provided with a one-piece rotary valve body that provides an efficient control for a liquid free from undesirable leakage and which valve is easier to turn than heretofore in valves of the same general type of one-piece plug valves.

In the drawings,

Fig. 1 is an elevational view of the nozzle showing a spray tip and a straight nozzle tip on the ends of the discharge openings.

Fig. 2 is a sectional view through the nozzle of Fig. 1 but with the tips omitted.

Fig. 3 is a part elevational, part sectional view of the nozzle taken at right angles to the view in Fig. 2.

Fig. 4 is a sectional view through a modified form of nozzle showing a modified valve plug and valve structure.

In detail, referring to Figs. 1 to 3, the nozzle comprises a housing generally designated 1, provided with an inlet 2 opening outwardly of one side of the housing, and a pair of discharge passageways 3, 4 opening outwardly of the side of the housing that is generally opposite the inlet. Within the said housing is an enlarged chamber 5 in which is rotatably supported a valve body 6, which valve body is provided with a through port 7 and a port 8 at right angles to port 7 and communicating with the latter at a point centrally between its ends.

The outlet passageway 3 is preferably in axial alignment with the inlet passageway 2, and said inlet and outlet passageways open into chamber 5 at diametrically opposite points in the cylindrical walls 9 of said chamber, the remaining walls 10, 11 being flat and in opposed relation to each other.

The body 6 comprises the central segment of a ball having flattened parallel opposite sides adjacent walls 10, 11 respectively, and a circular periphery that conforms to spherical contour in cross section, as best seen in Fig. 3.

Coaxial trunnions 12, 13 project from opposite

5 sides of said body 6 coaxial with the latter, the trunnion 12 being rotatably supported in a recess 14 in wall 10, there being a yieldable rubber or composition disk 15 between the base of said recess and the end of trunnion 12.

The trunnion 13 extends through a central opening in wall 11 and through a stuffing box 16 to the outside of the housing where it is provided with a wing member or handle 17 for turning by the fingers of the hand.

10 The flat wall 11 comprises a disk that is threadly secured in an opening in the side of the housing, which opening is larger than the diameter of the body 6. Thus upon unscrewing the disk 11, and loosening a pair of coaxial sleeves at opposite sides of said body 6, as will later be explained, the valve body 6 may be freely withdrawn from chamber 5 without removing the handle 17 or unscrewing the stuffing box.

15 20 An annular thrust gasket or collar 18 of yieldable material, such as rubber or the like, is around the trunnion 13 between disk 11 and the plug body 6. While the end of trunnion 13 that extends through the disk 11 and stuffing box 16 is slightly smaller in diameter than the portion of the trunnion adjacent the body 6 and that is within collar 18, nevertheless the body 6 is yieldably held centered in the chamber 5 between walls 10, 11 by said collar 18 and the disk 15.

25 30 The spherical peripheral surface of the body 6 is spaced from the cylindrical walls 9 of chamber 5 by sleeves 20, 21 respectively reciprocable in the inlet passageway 2 and in the outlet passageway 3. These sleeves and the ports 7, 8 are all preferably of the same diameter.

35 40 Sleeves 20, 21 project into chamber 5 and their projecting ends are of a contour conforming to the spherical surface of the periphery of the body 6 and said ends are yieldably held in frictional engagement with said spherical surface by means of collars 23, 24 respectively, positioned between the opposite ends of sleeves 20, 21 and retainer rings 25, 26 that are respectively threaded in the inlet and outlet passageways adjacent enlarged interiorly threaded ends 27, 28 of said passageways.

45 50 The collars 23, 24 and rings 25, 26 are of the same internal diameter as the diameters of sleeves 20, 21. Rings 25, 26 are adapted to be rotated by a spanner or screw driver and by adjusting said rings relative to each other, the body 6 is substantially suspended between them so that there is little friction between the trunnions and their bearings. By retracting rings 25, 26 the sleeves 55 21, 20 will be loosened relative to body 6 a suffi-

cient degree to permit free withdrawal of the body from the chamber 5 after disk 11 is removed.

From the foregoing description it will be seen that there is a space between the body 6 and the walls of chamber 5 in which water pressure may be around body 6, but when the valve body is in closed position the water pressure in the inlet will tend to urge the body against the projecting end of sleeve 21. The frictional engagement between sleeve 21 and the body is practically all the resistance there is, although the trunnions may offer a little. However, the valve body may be rotated almost effortlessly by two fingers of the hand even though the water pressure against the body is say, 300 lbs. per square inch or more.

The spherical contour of the periphery of the body 6 and the corresponding contour of the projecting ends of the sleeves enables them to be quickly and easily reground in the field should leaks develop due to scoring of the body or sleeve ends from sand or other abrasive.

A straight nozzle tip 30 or other nozzle tip of any desired conformation may be quickly screwed into the threaded end 28 of the housing. Ordinarily this discharge passageway is for a solid stream.

The discharge passageway 4 preferably opens outwardly of housing 1 in the same direction as the discharge passageway 3, but it opens into the chamber 5 through cylindrical wall 9 at a point midway between sleeves 20, 21.

The side of housing 1 is formed with an enlargement 31 through which said passageway 4 extends and said passageway is enlarged at 32 adjacent the point where it opens into chamber 5.

Extending across said enlarged portion 32 in a direction at right angles to the axis of sleeves 20, 21 is a tubular screen 33 that is preferably of perforated metal. One end of said screen is secured in passageway 4 adjacent the point where it opens into chamber 5, while the other end is secured in a bore 34 that is coaxial with the screen and which bore opens outwardly of the enlarged portion 32. The bore 34 is threaded for a plug 35 that is adapted to be rotated by the fingers, and the inner end of said plug engages the end of screen 33 adjacent thereto. An outlet port 36 opens into bore 34 at a point normally closed by the sides of plug 35, but by unscrewing said plug a predetermined distance the port 36 is uncovered whereby any water entering the screen at its end opposite plug 35 will pass through the screen and out of port 36 thus cleaning the screen of any debris, etc.

Discharge passageway 4 continues from the enlargement 32 in gradually decreasing diameter, and angularly relative to the axis of the screen 33 through an exteriorly threaded projection 36' that extends in the same direction as the discharge end 28 of the main body, and substantially alongside said end 28. A spray or fog nozzle tip 38 is adapted to be screwed onto projection 36, or any other desired nozzle tip may be screwed onto said projection.

All water or liquid passing to the spray nozzle 38 must pass through the screen 33, therefore the spray nozzle will not be clogged by debris and rendered useless at a critical time. If the screen should become clogged, it can be quickly cleaned by merely partially unscrewing the plug 35.

The port 8 in the body 6 functions to deliver water or liquid to the discharge passageway 4

when the body 6 is turned to close passageway 3 and to place port 8 in registration with the inlet sleeve 20. When the body is turned to the position seen in Fig. 2, both discharge ports are closed, and by rotating the body 6 clockwise (as seen in Fig. 2) the port 7 is aligned with sleeves 20, 21 while passageway 4 is closed.

In the form illustrated in Fig. 4, the housing 40 substantially resembles the body 1, but the screen 33 and plug 35 are omitted, also the discharge passageway 3 (indicated at 41 in Fig. 4) does not have a sleeve. Instead of such sleeve, the body 42 (similar to body 6) is formed with a bore 43 in axial alignment with the port 44 (corresponding to port 8). The bore 43 is interiorly threaded for a member 45. A plug 46 projects from the bore 43 and is formed with a curved outer surface that is adapted to slidably engage the cylindrical surface of chamber 5. A yieldable disk 47 of rubber or the like, is interposed between member 45 and plug 46 so as to hold the outer surface of the plug in yieldable engagement with said cylindrical surface of chamber 5.

Except for the above, the structure is the same as in Figs. 1 to 3 and the same numbers are used to designate corresponding parts.

The pressure of plug 47 on the walls of chamber 5 is adjusted by rotation of the member 43 until the body 42 is practically suspended between said plug and sleeve 20. While the plug 47 does not always remain at a point diametrically across chamber 5 from the sleeve 20, nevertheless it functions to relieve the friction between the trunnions and the housing sufficiently to make an easy operating valve.

It is to be understood that the detailed description and drawings are not to be considered restrictive of the invention, but merely illustrative thereof.

I claim:

1. A dual discharge nozzle comprising a housing formed with an inlet passageway having one of its ends opening outwardly of said housing at one side of the latter and formed with a pair of discharge passageways each having an end opening outwardly of said housing at the opposite side of said housing, an enlarged chamber formed in said body with which one end of each said passageways communicate, a valve body rotatable in said chamber formed with ports arranged for establishing communication between either and both of said discharge passageways and said inlet passageway as desired upon rotating said body about its central axis to predetermined positions, a tubular screen disposed within one discharge passageway of said pair and extending radially of said axis and coaxial with the port in said body that is adapted to communicate with said one discharge passageway when said body is turned to effect such communication, the walls of said one discharge passageway being enlarged around said screen intermediate the ends of said screen and said one discharge passageway extending from said enlarged portion to its end that opens outwardly of one side of said housing, a clean-out passageway formed in said housing communicating between the end of said screen that is outwardly of said valve body and the outside of said housing, and a valve in said clean out passageway for opening and closing the latter to flow of fluid therethrough.
2. A dual discharge nozzle comprising a housing formed with an inlet passageway having one

of its ends opening outwardly of said housing at one side of the latter and formed with a pair of discharge passageways each having an end opening outwardly of said housing at the opposite side of said housing, an enlarged chamber formed in said body with which one end of each of said passageways communicate, a valve body rotatable in said chamber formed with ports arranged for establishing communication between either and both of said discharge passageways and said inlet passageway as desired upon rotating said body about its central axis to predetermined positions, a tubular screen disposed within one discharge passageway of said pair and extending radially of said axis and coaxial with the port in said body that is adapted to communicate with said one discharge passageway when said body is turned to effect such communication, the walls of said one discharge passageway being enlarged around said screen intermediate the ends of said screen and said one discharge passageway extending from said enlarged portion to its end that opens outwardly of one side of said housing, a bore formed in said housing coaxial with said screen at the end of the latter that is outwardly of said valve body, a clean-out passageway communicating between the outside of said housing and said bore at a point intermediate the ends of the

latter, a plug threadedly secured on said bore for movement thereon to positions opening and closing said clean-out passageway, and said screen being removable through said bore when said plug is removed.
